UNITED STATES PATENT OFFICE.

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT.

TOOL-RACK.

1,097,163.

Specification of Letters Patent. Patented May 19, 1914.

Application filed June 27, 1912. Serial No. 706,223.

To all whom it may concern:

Be it known that I, ROBERT S. BROWN, a citizen of the United States, residing at New Britain, in the county of Hartford and 5 State of Connecticut, have invented certain new and useful Improvements in Tool-Racks; of which the following is a specification.

This invention relates to what I shall for 10 convenience term a "tool rack," among the objects of the invention being the provision of a device of this character which is simple yet strong in construction and which can be readily and easily made, and the parts there- 15 of quickly assembled.

In the drawings accompanying and forming 20 part of the present specification I have shown in detail one of the several convenient forms of embodiment of the invention, which to enable those skilled in the art to practise the same will be fully set forth in the following description, while the novelty of the invention will be set forth in the 25 claims succeeding said description. From this it will be clear that I do not restrict myself to such disclosure; I may depart there- 30 from in several respects within the scope of the invention defined by said claims.

Referring to said drawings: Figure 1 is 35 a perspective view of a tool rack involving my invention. Fig. 2 is a top plan view of one corner of the upper shelf of the rack. Fig. 3 is a side elevation of the parts shown in Fig. 2. Fig. 4 is a top plan view of another corner of the upper shelf of the rack. Fig. 5 is a longitudinal sectional view of Fig. 4. Fig. 6 is a sectional view of one 40 corner of the intermediate tray of the rack. Fig. 7 is a top plan view of the parts shown in Fig. 6. Fig. 8 is a sectional view of the parts shown in Fig. 7, and, Fig. 9 is a sectional view of a swivel member and wheel.

Like characters refer to like parts 45 throughout the several figures of the drawings.

A tool rack involving my invention is 50 preferably, but not necessarily portable, and when portable presents a truck; any suitable wheel means may be provided for supporting the rack, although those illustrated and hereinafter described are satisfactory. The rack usually involves several trays, although it is conceivable that only one of such trays might be provided. In the con-

struction shown, however, there are three of 55 such trays, and they are designated respectively commencing with the lowermost as 10, 11 and 12. Although they may be of any suitable shape and construction they are shown as practically rectangular in top plan- 60 and as being substantially of pan form so as to effectively receive tools, implements and the like which blacksmiths and other artisans use in their work. Said trays or 65 pans are preferably of steel and are also seamless thus preventing leakage therefrom.

For supporting the trays or shelves 10, 11 and 12 any suitable means may be provided, for instance rods as 13, 14, 15 and 16, these rods being disposed in the present instance vertically and being located approximately at the corners of the superposed trays. The means for connecting the rods with the trays will be hereinafter more particularly described, and I might say that the 75 same constitutes one of the important features of the invention.

The lowermost tray is provided with suitable bearings as 17 for receiving the axle 18 equipped at its ends with the wheels 19. The 80 rear rods 15 and 16 extend below the lowermost tray 10 and are stepped in the swivel members 20 furnished with wheels 21. The tool rack can, therefore, be easily moved from place to place. 85

Each of the trays 10, 11 and 12 has at its rim portion a practically continuous groove or channel 22, and this channel or groove can be produced by flanging the trays or shelves outwardly and downwardly as at 23, 90 said channels or grooves 22 being preferably laterally enlarged and rounded somewhat to receive the corner bearing members or blocks 24 which as will be understood fit snugly said laterally enlarged portions of 95 the grooves or channels 22. The blocks 24 are practically cylindrical in form and are partly covered and hidden by the flanges 23. This construction also materially strengthens said trays or pans. Owing to the rounding 100 of the trays or pans at their corners it becomes an easy matter to clean the same. Said bearing members or blocks 24 are shown provided with outwardly-extending wings 25 which project therefrom at approximately right angles to each other and 105 fit closely in the respective channels 22, said wings 25 being preferably rigidly united in

some suitable manner to the respective trays, for example by means of rivets 26. These corner bearing members or blocks present a very simple way of connecting rods 13, 14, 15 and 16 with the rack and in turn they are saidly and firmly held in place. The rods 13 and 14 are driven into the two front blocks 24 on the tray 10, while the rods 15 and 16 extend entirely through the blocks at the forward end of said tray 10, being as already described, connected with the swivel members 20. All four of the rods 13, 14, 15 and 16 extend freely through the blocks 24 on the intermediate tray so as to provide for the ready adjustment of said intermediate tray, said rods for this purpose being preferably peripherally plain where they pass through the intermediate bearing members. The adjustment of the intermediate tray can be maintained by set screws 27 tapped into the intermediate blocks and adapted to engage the respective rods 13, 14, 15 and 16. The upper ends of said rods are tapped into the uppermost blocks or bearing members 24. The uppermost bearing blocks 24 to which the rods 13 and 15 are connected, are shown provided with outwardly extending arms 28 and 29, while the uppermost bearing blocks to which the rods 14 and 16 are connected, are furnished with arms 30 and 31 extending outward therefrom at an angle and associated with these several arms is a yoke as 32 which is shown fitted between its ends in notches 33 in the outer ends of the arms 30 and 31, and the terminals of which are driven or tightly fitted in openings in the arms 28 and 29. This yoke can be utilized to sustain tools and can also act as a handle for the rack or truck. The axle supporting brackets or bearings 17 in the construction shown, are integral with the wings 25 of the lowermost front blocks 24.

From the foregoing description taken in connection with the annexed drawings it will be evident that my tool rack comprises a substantially rectangular pan having a stiffened edge in connection with an axle support fastened to said stiffened edge on

two sides of the said pan, the lower pan being thus made.

What I claim is:

1. A tool rack comprising a shelf grooved in the under side thereof, and blocks fitted into the grooved portion of the shelf and provided with laterally extending wings rigidly connected with said shelf.

2. A tool rack comprising a shelf having a substantially continuous groove in the under side thereof, blocks set into said groove, provided with laterally extending wings rigidly connected with the shelf, and shelf-supporting rods connected with the respective blocks.

3. A tool rack comprising a substantially rectangular shelf having an approximately continuous groove in the under side thereof laterally enlarged and rounded at the corners, and cylindrical blocks fitted in the laterally enlarged portions of the groove, provided with wings attached to said shelf.

4. A tool rack comprising a substantially rectangular pan-like shelf having a marginal flange to form a practically continuous groove in the under side of the shelf, said groove being laterally enlarged and rounded at the corners of the shelf, and cylindrical blocks fitted in the enlarged portions of the groove, provided with wings riveted to the flange portion of the shelf.

5. A tool rack comprising an approximately rectangular pan having a stiffened edge combined with angular axle supports fitted around the corners of the pan at the stiffened edge thereof.

6. A tool rack comprising an approximately rectangular pan grooved in its under side, and rod receiving blocks fitted in the grooved part of the pan at the corners thereof, extending around said corners and provided with axle supporting brackets rigid therewith.

In testimony whereof I affix my signature in presence of two witnesses.

ROBERT S. BROWN.
